(57) **CLAIM**

The ornamental design for an embellishing plate for snips, as shown and described.

DESCRIPTION

FIG. 1 is a perspective view of an embellishing plate for snips showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dash-dash broken lines shown in the drawings depict portions of the embellishing plate for snips that form no part of the claimed design. The dash-dot broken lines in the drawings depict the boundaries of the claimed design.

1 Claim, 8 Drawing Sheets
